UNITED STATES PATENT OFFICE

EMANUEL YOSS, OF RICHMOND, VIRGINIA

TURBINE PUMP

Application filed July 28, 1928. Serial No. 295,989.

This invention relates to a turbine pump for use with either liquid or air, the general object of the invention being to provide a rotor or impeller of frusto-conical shape operating in a casing of similar shape, the impeller having a concentrically arranged annular groove at its center in which are placed blades forming pockets and the casing having a concentrically arranged groove therein located opposite the groove in the impeller, the ends of said groove being in communication with inlet and outlet chambers formed in the casing and of circular shape in cross section, the chambers being parallel to each other and to the axis of the device, with means for so forming the grooves and so arranging the blades that a spiral motion is imparted to the fluid as it passes from the inlet chamber to the outlet chamber and a rotary motion is imparted to the fluid in each chamber.

Another object of the invention is to so arrange the parts that when the device is used as an air pump, and a certain amount of liquid is placed in the device, the centrifugal action of the impeller on the liquid in the inlet chamber will cause the liquid to form vacuum spaces in the pockets which act to draw air into the same so that this air will be caused to flow from the inlet chamber to the outlet chamber, where the liquid, under the action of centrifugal force, will cause the air to leave the pockets and thus pass off through the outlet.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like

or corresponding parts throughout the several views, and in which:—

Figure 1 is a front view of the device, with parts broken away.

Figure 2 is a section on line 2—2 of Figure 1.

Figure 3 is a section on line 3—3 of Figure 1.

Figure 4 is a view looking into the casing.

Figure 5 is a face view of the impeller, looking toward the small end thereof.

Figure 6 is an edge view of the impeller.

Figure 7 is a diagrammatic sectional view.

Figure 8 is an enlarged detail sectional view showing the cross sectional shape of the grooves in the impeller and casing.

In these views, the numeral 1 indicates a casing forming a chamber of frusto-conical shape and 2 indicates a cover plate for enclosing the chamber of the casing, this cover plate being bolted to the casing, as shown.

A shaft 3 passes through the chamber of the casing and has one end journaled in the small end of the casing, as shown at 4, and its other end is journaled in the center of the cover plate, as shown at 5. An impeller or rotor 6 of frusto-conical shape is fastened to the shaft with its sloping walls contacting

with the sloping walls of the chamber. The upper part of the casing is formed with a cylindrical inlet chamber 7 and a similar shaped outlet chamber 8, these chambers having their axes parallel with each other

and with the axis of the device, with the lower inner portions of the chambers having substantially elliptical-shaped openings 9 therein which place the chambers in communication with the ends of a concentric groove

10 formed in the interior wall of the casing substantially midway the ends of the frusto-conical chamber formed by the casing. This groove is of substantially semi-elliptical form with its larger peripheral portion being formed with a curvature of less radius

60

65

70

75

80

85

than its smaller peripheral portion, as clearly shown in Figure 8. As shown in Figure 7, the smaller peripheral portion of this groove merges into the lower inner walls of the openings 9.

The impeller is formed with a concentrically arranged groove 11 in its sloping face substantially midway its ends, this groove being of substantially triangular shape in cross section with one wall parallel with the axis of the device and the other wall arranged at right angles to the axis. This groove is arranged opposite the groove 10 and a plurality of blades 12 is carried by the impeller and intersect the groove 11. These blades are arranged on a tangent, as shown, with their outer edges flush with the sloping surface of the impeller. As shown, the blades are set in the groove with their edges at a retarded angle of substantially twelve degrees (12°) at the large diameter of the groove and they are also set at an advanced angle in the direction of rotation of the impeller. As shown in Figure 7, the groove 10 extends substantially two-thirds around the circumference of the interior wall of the casing, with that portion of the casing between the inlet and outlet chambers solid so as to leave a sealing portion between said inlet and outlet chambers.

A small casing 13 has an elbow part 14 connected with each inlet and outlet chamber.

As shown in Figure 3, portions of the walls of each chamber 7 and 8 are in alignment with portions of the groove 11 so that a portion of said groove forms a portion of each chamber and thus the blades pass through the chambers during the rotation movement of the impeller.

From the foregoing it will be seen that during the rotation of the impeller, the blades thereon will set up a rotary motion of the liquid in the inlet and outlet chambers, as shown by the arrows in Figure 7, and the centrifugal action will cause the liquid in the inlet chamber to enter the pockets formed by the blades of the impeller as the pockets move to the opening 9 of said inlet chamber and then this liquid is forced by centrifugal action from the pockets as the pockets advance through the opening 9, so that vacuum spaces will occur in the pockets, which will act to draw air into the same when the device is used as an air pump, it being understood that in this case, sufficient liquid is placed in the device to fill the cavities thereof. As the pockets containing the air pass within the grooves of the device, the liquid and air is given a spiral movement through the grooves, as shown by the arrows in Figures 7 and 8, until the fluid reaches the outlet chamber. The liquid in this chamber is also rotating, as shown by the arrows in Figure 7, and as the pockets

enter the chamber, the centrifugal action of the liquid will cause said liquid to enter the pockets and force the air therefrom and thus the air will pass through the outlet and the pockets will be filled with liquid and this liquid will pass into the inlet chamber as the impeller revolves. As shown in Figures 7 and 8, the centrifugal action will force the fluid from the pockets into the groove 10, and the peculiar shape of this groove will give the fluid a spiral motion and return it to the pockets and thus the fluid will be forced from the inlet to the outlet with a spiral motion of considerable force.

Substantially the same action takes place when the pump is used as a liquid pump, but in this case as the liquid is under a head, the pockets will be filled with liquid as the impeller passes from the inlet chamber into the grooved part of the device and this liquid will be given a spiral forward movement through the grooves to the outlet chamber.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A pump of the class described comprising a casing having a frusto-conical chamber therein, an impeller of frusto-conical shape located in the chamber, said impeller having a concentric groove in its peripheral part, blades in the groove forming pockets, said groove being of substantially triangular shape in cross section with one wall parallel with the axis of the impeller and the other at right angles to the axis, the internal wall of the casing having a concentrically arranged groove therein of substantially semi-elliptical shape in cross section opposite and in communication with the groove in the impeller, inlet and outlet chambers with which the ends of the groove in the casing are in communication, said chambers being arranged parallel with each other and with the axis of the device and of cylindrical formation, the intersection of the groove in the casing with the inlet and outlet chambers forming elliptical shaped ports which place said chambers in communication with the groove whereby the blades will enter the chambers and act on the fluid therein.

2. A pump of the class described comprising a casing having a frusto-conical chamber therein, an impeller of frusto-conical shape located in the chamber, said impeller having a concentric groove in its peripheral part, blades in the groove forming pockets, said groove being of substantially triangular

lar shape in cross section with one wall parallel with the axis of the impeller and the other at rightangles to the axis, the internal wall of the casing having a concentrically arranged groove therein of substantially semi-elliptical shape in cross section opposite and in communication with the groove in the impeller, inlet and outlet chambers with which the ends of the groove in the 5 casing are in communication, said chambers being arranged parallel with each other and with the axis of the device and of cylindrical formation, the blades in the impeller being tangentially arranged with their outer 10 edges at a retarded angle at the larger diameter of the groove and said blades being set at an advanced angle in the direction of rotation.

3. A pump of the class described comprising a casing having a frusto-conical chamber therein, an impeller of frusto-conical shape located in the chamber, said impeller having an annular groove in its peripheral part, blades in the groove forming pockets, 20 the internal wall of the casing having an annular groove therein opposite and in communication with the groove in the impeller, inlet and outlet chambers with which the ends of the groove in the casing are in communication, said chambers having their axes arranged parallel with each other and with the axis of the device and of cylindrical 25 formation.

4. A pump of the class described comprising a casing having a frusto-conical chamber therein, an impeller of frusto-conical shape located in the chamber, said impeller having a concentric groove in its peripheral part, blades in the groove forming pockets, 30 said groove being of substantially triangular shape in cross section, with one wall parallel with the axis of the impeller and the other at rightangles to the axis, the internal wall of the casing having a concentric groove 35 therein opposite and in communication with the groove in the impeller, inlet and outlet chambers with which the ends of the groove in the casing are in communication, said chambers being of cylindrical formation 40 and having their axes arranged parallel to the axis of the device, with portions of the side and bottom walls of each chamber in alignment with portions of the walls of the groove in the impeller whereby said portions 45 of the groove form a part of the chamber.

5. A turbine pump comprising a casing having a substantially conical shaped chamber therein having a concentric groove in its 50 interior wall, a substantially conical shaped impeller rotatably mounted in the casing and having a concentric groove in its periphery arranged opposite and in communication with the first mentioned groove, 55 blades carried by the impeller and dividing

the groove therein into pockets, a cylindrical inlet chamber connected with one end of the groove in the casing and having its axis parallel with the axis of the device, portions of the walls of the groove in the 60 impeller forming continuations of portions of the walls of the chamber whereby portions of said groove form a part of the chamber and outlet means connected with the other end of the groove in the casing. 65

In testimony whereof I affix my signature.
EMANUEL YOSS.
